US00D743399S

(12) **United States Design Patent**
Frank

(10) **Patent No.:** **US D743,399 S**
(45) **Date of Patent:** **** Nov. 17, 2015**

(54) **FLASH MODULE**

(71) Applicant: **EMC Corporation**, Hopkinton, MA (US)

(72) Inventor: **Christopher Frank**, Menlo Park, CA (US)

(73) Assignee: **EMC Corporation**, Hopkinton, MA (US)

(**) Term: **14 Years**

(21) Appl. No.: **29/492,424**

(22) Filed: **May 30, 2014**

(51) **LOC (10) Cl.** **14-02**

(52) **U.S. Cl.**

USPC **D14/435**; D14/436; D14/480.1

(57) **CLAIM**

The ornamental design for a flash module, as shown and described.

DESCRIPTION

FIG. 1 is a first perspective view of a flash module showing the new design;

FIG. 2 is a second perspective thereof;

FIG. 3 is a side view thereof;

FIG. 4 is a top view thereof;

FIG. 5 is a bottom view thereof;

FIG. 6 is a front view thereof;

FIG. 7 is a reduced front perspective view of the bezel portion of the flash module; and,

FIG. 8 is a rear view thereof.

Broken lines and unshaded portions contained within broken lines are not claimed.

1 Claim, 5 Drawing Sheets
